M. E. THOMAS

DRILL

Filed Oct. 8, 1923

Inventor
Martin E. Thomas,

By
Geo. P. Kimmel, Attorney

UNITED STATES PATENT OFFICE.

MARTIN E. THOMAS, OF STRATFORD, OKLAHOMA, ASSIGNOR OF ONE-FOURTH TO J. L. GRAY, OF BRITTON, OKLAHOMA, ONE-EIGHTH TO G. C. ARNOLD, ONE-EIGHTH TO W. L. ALLEN, AND ONE-FOURTH TO IDA F. HASLEY, OF OKLAHOMA CITY, OKLAHOMA.

DRILL.

Application filed October 8, 1923. Serial No. 667,276.

To all whom it may concern:

Be it known that I, MARTIN E. THOMAS, a citizen of the United States, residing at Stratford, in the county of Garvin and State of Oklahoma, have invented certain new and useful Improvements in Drills, of which the following is a specification.

This invention relates to improvements in drills of the well boring type and has for its object to provide an improved guide sleeve carried by the drill rod adjacent the drill head which is of such diameter as to approximately fit the bore and, being engaged with the wall thereof, prevents vibratory movement of the drill incident to variations in the quality or character of the earth or rock and the consequent possible impairment in efficiency of operation of the boring tool.

Further objects of the invention are to provide, in a manner as hereinafter set forth, a drill for well boring and which is simple in its construction and arrangement, strong, thoroughly efficient in its use, readily assembled, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 represents a side elevation of the improved drill, partly in longitudinal section, and

Figure 2 represents a transverse sectional view on the line 2-2 of Figure 1.

Referring to the drawing in detail, wherein similar reference numerals designate corresponding parts throughout the several views, the numeral 5 indicates the usual hollow tubular drill rod having one extremity thereof for engagement with the threaded coupling ring 6, the bore of which is threaded throughout a portion of its length to fit the threaded terminal of the rod 5 and is gradually restricted inwardly from its opposite end to provide tapered

portion 7. The internal reduction of the coupling ring provides an internal annular shoulder constituting an abutment for the terminal of the rod 5. The tapered portion of the bore of the ring receives the correspondingly tapered and externally threaded terminal of the drill head 8, the opposite extremity of which is enlarged as indicated at 9 and supports a plurality of cutting disks 10 rotatably supported upon bolts 11 threaded in the relatively large terminal of the head 8.

Three cutting disks 10 are preferably provided and are arranged at intervals of 120 degrees to provide for uniformity of spacing and the axes of the disks are preferably disposed in upwardly converging relation whereby to secure maximum cutting or drilling efficiency thereof.

A stop collar 12 is formed integral or otherwise rigidly secured to the tubular drill rod 5 above the coupling ring 6 and coacts therewith to confine the guide sleeve 14 which is also of tubular form and is arranged in concentrically spaced relation to the rod 5 being supported in position by groups of radially disposed spacing elements engaged with the outer surface of the rod 5 and effectively confined between the coupling 6 and the collar 12 to prevent longitudinal displacement of the sleeve 14. Each of the spacing elements consists of a stem 13 having its outer end formed integral with the inner face of a curved outer head plate 13', and its inner end formed integral with the outer face of a curved inner head plate 13''. The head plates are arranged concentrically with respect to each other and the stem is positioned centrally with respect to each plate. Each of the plates is of a length and width materially greater than the diameter of the stem. The plate 13' abuts against and is secured to the inner face of the sleeve 14, and the plate 13'' abuts against and is secured to the outer face of the rod 5. Screws or other types of removable fastening elements 15 are employed to connect the opposite head plates of the spacing elements with the rod 5 and the sleeve 14, respectively, so as to prevent relative rotation of the rod and sleeve.

The internal diameter of the sleeve 14 is approximately equal to the size of the bore produced during operation of the drill

whereby the contact established between the external surface of the sleeve and the wall of the bore effectively prevents such excessive vibratory movement of the drill head as would impair the efficiency thereof, especially when boring through such relatively hard materials as rock and the like. The usual water pipe 14 arranged in the head 8 and the discharge terminal thereof is arranged in direct alignment with the longitudinal axis of the head so as to discharge water at a point centrally between the cutting disks 10.

What I claim is:

1. A drill comprising a drill rod, a guide sleeve receiving said rod, a threaded coupling ring removably secured to the lower end of said rod, a stop collar rigidly secured to said rod and spaced a substantial distance from said ring, said collar and ring limiting the longitudinal movement of the guide sleeve thereon, spacing elements interposed between the rod and sleeve maintaining the latter in concentrically spaced relation to the rod.

2. A drill comprising a drill rod, a guide sleeve receiving said rod, a threaded coupling ring connected to the lower end of said rod, a collar fixedly secured to the rod a substantial distance from each ring, said collar and ring providing confining elements on the rod for limiting the longitudinal movement of the guide sleeve thereon, said ring being removable to permit removal of the guide sleeve, spacing elements interposed between the guide sleeve and rod, and means as

sociated with the spacing elements and coacting with the rod to prevent relative rotation of the latter and the guide sleeve.

3. A drill comprising a drill rod, a drill head, a guide sleeve disposed concentrically with respect to said rod, a pair of confining elements carried by the rod for limiting the longitudinal movement of the guide sleeve thereon, one of said confining elements coupling the drill head to the rod, and spacing elements interposed between the rod and the sleeve for maintaining the latter in spaced relation with respect to the rod, said spacing elements abutting against said confining elements.

4. A drill comprising a drill rod, a drill head, a guide sleeve disposed concentrically with respect to said rod, a confining element removably connected to the lower end of said rod, a confining element rigidly secured to the rod and spaced from the other confining element, spacing elements interposed between the rod and sleeve for maintaining the latter in spaced relation with respect to the rod, said spacing elements abutting against said confining elements for limiting the longitudinal movement of the guide sleeve on the rod, and each of said spacing elements provided with an outer and an inner curved head plate, means for removably securing the inner head plates to the rod, and means for removably securing the outer head plates to the sleeve.

In testimony whereof, I affix my signature hereto.

MARTIN E. THOMAS.
